TYPEWRITER ATTACHMENT

John Q. Sherman, Dayton, Ohio

Application June 30, 1933, Serial No. 678,450

10 Claims. (Cl. 197—133)

This invention relates to writing machines and particularly to a holder for a paper supply of continuous series connected stationery to be mounted directly upon a typewriter. It is recognized that there have been numerous holders for supplies of paper or record material, some of which have been mounted for to and fro travel with the typewriter platen carriage, while others have been stationary and provided with various devices for withdrawing and guiding the record material to the platen roll. Such devices have usually been of expensive construction and occupy considerable space, more than is available on an ordinary typewriter desk or stand.

The present apparatus contemplates an adjustable holder for continuous strips of record material to be stationarily secured to the frame of a typewriter and an upstanding guide frame carried by the traveling platen carriage of the typewriter, of sufficient height that the twisted or askew position assumed by the supply portion of a strip of record material, as the traveling platen carriage reaches the limit of its travel, will not be transmitted to that portion of the supply strip in proximate relation to the platen roll.

The object of the present invention is to simplify the construction as well as the means and mode of operation of stationery holding and supply devices for writing machines, whereby they will not only be cheapened in construction, but will be more efficient in use, effective in operation, easily applied to ordinary commercial typewriters, and unlikely to get out of repair.

A further object of the invention is to provide a construction which will be compact in form and capable of being easily contained in an ordinary typewriter desk.

A further object of the invention is to provide a stationery holder or receiver for a paper supply directly applicable to a typewriter structure and a guiding means intermediate the holder or receiver and the platen roll of the typewriter which will insure sufficient length of supply strip between the holder and the platen roll to obviate any uneven tension, pulling or twisting of the supply material adjacent to the platen roll and consequent interference with uniform feeding movement.

A further object of the invention is to provide retractable guide means which will enable a desk to be closed over the typewriter or a cover of ordinary form to be placed thereover.

A further object of the invention is to provide an apparatus having the hereafter mentioned

features of advantage and improved mode of operation.

With the above primary and other incidental objects in view, as will more fully appear in the specification, the invention consists of the features of construction, the parts and combinations thereof, and the mode of operation, or their equivalents, as hereinafter described and set forth in the claims.

In the accompanying drawings, wherein is shown the preferred but obviously not necessarily the only form of the embodiment of the invention, Fig. 1 is a side elevation of a well known typewriter construction to which the present invention has been applied. Fig. 2 is a perspective view, showing the relation of the paper holder and guide means to the typewriter structure. Fig. 3 is a perspective view of the paper guiding devices. Fig. 4 is a perspective view of the paper supply holder. Fig. 5 is a perspective view of the base or supporting member.

Like parts are indicated by similar characters of reference throughout the several views.

Referring to the accompanying drawings, 1 is a typical writing machine of which 2 is the usual reciprocatory platen carriage and 3 the platen roll carried thereby.

Secured to the rear of the typewriter 1 is the paper supply holder, forming the subject matter hereof. Such paper holder includes the base or supporting member 4 which, in the present instance, is a plate having its rear margin bent to form an upwardly and rearwardly extending flange 5. At its forward edge the base or supporting member 4 is provided with clamps 6 by which the base is fixedly, but detachably, engaged with the frame of the typewriter 1.

Detachably mounted upon the base 4 is the paper supply holding member which consists of a metal plate bent into angular formation to afford a back panel 7 and a shelf-like extension 8 at the bottom of the back panel 7, the forward margin of such shelf 8 being preferably, though not necessarily, deflected upwardly as at 9. This paper holder, comprising the unitary back panel 7 and shelf 8 is mounted in a rearwardly inclined position upon the base or support 4 whereby the back panel 7 is disposed in an upwardly and rearwardly inclined position while the shelf 8 projects forwardly and upwardly. The unitary holder is detachably engageable with the base 4 by any suitable means which, for convenience and economy of manufacture, are preferably, though not necessarily, headed studs 10 upon one of these

members which engage within key-hole slots 11 in the other member.

The back panel 7 of the paper holder is provided with transverse slots 12 within which are 5 adjustably mounted vertical guide flanges 13. The flanges 13 are adjustable toward and from each other to agree with the lateral dimensions of a packet of record material positioned upon the shelf 8 and resting against the back panel 10 7 intermediate such flanges 13. The paper supply holder is stationary relative to the typewriter 1. If the paper supply should be drawn direct from the holder or carrier to the platen roll 3, the movement of the traveling typewriter carriage 2 would pull the paper strip askew, first in 15 one direction and then in the other as it approached the limit of its travel in either direction, and so cause the supply strip of record material to be torn or cause undue pulling strain which 20 would tend to induce uneven tension upon that portion engaged by the platen roll and so cause misalignment or improper feeding of the material through the writing machine. To obviate such condition by insuring an ample length of 25 paper supply strip between the holder and the platen roll, guiding means is mounted upon the traveling carriage over which the supply strip passes. As illustrated in the drawings, this guiding means comprises a pair of upwardly extending 30 parallel arms 14 hinged at 15 to brackets 16 secured to the traveling carriage of the typewriter 1. The brackets 16 are shaped and proportioned according to the construction of the particular typewriter to which they are to be applied, and are preferably provided with holes 35 registering with corresponding holes in the typewriter platen carriage whereby attachment screws, forming part of the typewriter structure and provided at the time of manufacture thereof, 40 may be utilized for the attachment of the brackets 16 for support of the guide arms 14.

At their upper ends the guide arms 14 carry a transverse rod 17 which is preferably, though not necessarily, longitudinally adjustable in the side 45 arms 14 to which it is secured by set screws 18. The paper supply strips, from the holder or carrier at the rear of the typewriter, pass over the rod 17 and thence downwardly to the platen roll 3. There is thus insured an ample length of 50 material between the holder and the platen roll to accommodate any twisting movement or lateral pulling action due to the to and fro travel of the platen roll carriage without transmitting such pulling strain to the platen roll itself. Limit 55 fingers 19 are provided and slidingly adjustable upon the rod 17 to retain the paper strip or strips in proper relation with the platen roll. These limit fingers 19 project inwardly toward each other and in overhanging relation with the paper 60 strip or strips, from supporting hubs or collars 20 mounted upon the transverse rod 17 to which they are secured in proper relatively adjusted position by set screws 21.

The present paper holder is especially designed 65 to accommodate continuous or series connected stationery which has been folded to and fro in zigzag formation into a supply packet. It is especially desirable and applicable to the use of manifolding material comprising superposed alternating strips of record and transfer material 70 folded in such zigzag formation into a supply packet of multiple strips. While in practice these strips are usually marginally punched for use with a pin type platen roll whereby absolute registry of superposed printed forms upon the sev-

eral strips is insured, the use of such pin type feeding devices and marginally punched paper is not material nor essential to the function of the paper supply holder and guiding means, but these may be employed with an ordinary friction feed 5 typewriter or other writing machine.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means 20 and construction herein disclosed comprise the preferred form of several modes of putting the invention into effect, and the invention is therefore claimed in any of its forms or modifications within the legitimate and valid scope of the appended claims.

Having thus described my invention, I claim:

1. The combination with a writing machine and a stationary paper supply holder therefor, of a vertically extending guide frame carried by the reciprocating platen carriage of a writing machine, said frame including upwardly extending side arms hinged to mounting members detachably engaging a platen carriage of a writing machine and a cross rod carried by the side arms 35 over which the paper supply is freely drawn from the holder to the platen, said cross rod being elevated sufficient distance above the platen to insure an ample length of paper supply between the holder and platen to prevent uneven tension 40 of the portion engaging the platen.

2. The combination with a writing machine and a stationary paper supply holder therefor, of a vertically extending guide frame carried by the reciprocating platen carriage of a writing machine, including upwardly extending side arms, mounting members detachably engageable with the platen carriage of a writing machine to which the arms are pivotally connected, and a cross rod adjustably mounted in said arms over 45 which a paper supply is drawn from the holder to the platen.

3. The combination with a writing machine and a stationary paper supply holder therefor, of a vertically extending guide frame pivotally carried by the reciprocating platen carriage of a writing machine, said guide frame including upwardly extending side arms, mounting members detachably engageable with the platen carriage of a writing machine to which the arms are pivotally connected, and a cross rod adjustably mounted in said arms over which a paper supply is drawn from the holder to the platen, said frame being of sufficient height above the platen to insure an ample length of paper supply between the holder and the platen to prevent uneven tension upon the portion engaged with the platen.

4. As an article of manufacture a stationery holder for a typewriter including an upwardly and rearwardly extending back panel, and an upwardly and forwardly extending shelf portion at the bottom of the panel to receive a packet of stationery which rests against the back panel, forwardly projecting flanges adjustably mounted 75

5 on the back panel for to and fro adjustment toward and from each other, a base plate upon which the back panel and shelf are stationarily positioned, attachment means for connecting the base plate fixedly with the frame of a typewriter, the back panel and shelf being detachably engageable in fixed relation with the base plate.

10 5. As an article of manufacture a stationery holder for a typewriter including a plate bent into angular formation and forming an integrally united back panel and a shelf at the bottom of the panel, forwardly projecting flanges adjustably mounted on the back panel for to and fro adjustment toward and from each other, and supporting means fixedly engaged with the typewriter frame for stationarily supporting the integral back panel and shelf in a rearwardly inclined position behind a typewriter.

15 6. As an article of manufacture a stationery holder for a typewriter including a plate bent into angular formation and forming an integrally united back panel and a shelf at the bottom of the panel, forwardly projecting flanges adjustably mounted on the back panel for to and fro adjustment toward and from each other, supporting means fixedly engaged with the typewriter frame for stationarily supporting the integral back panel and shelf in a rearwardly inclined position behind a typewriter, one of said members having key hole slots therein, and headed studs carried by the other member for engagement in the key hole slots for detachably connecting the unitary back panel and shelf with the support.

20 35 7. As an article of manufacture a pair of parallel arms to be carried in upstanding relation upon the traveling platen carriage of a typewriter, supporting brackets to which the arms are pivoted for forward folding motion, said brackets having holes therein agreeing with screw holes provided in the typewriter carriage at the time of manu-

facture whereby the brackets are engageable with the carriage by screws originally provided therein, a cross rod adjustably mounted in said arms, and retainers adjustably mounted on the cross rod.

5

8. As an article of manufacture a pair of parallel arms to be carried in upstanding relation upon the traveling platen carriage of a typewriter, supporting brackets to which the arms are pivoted for forward folding motion, said brackets being 10 mounted upon the typewriter carriage and held in position by screws originally provided in the carriage and guiding means adjustably carried by the arms.

15 9. The combination with a conventional writing machine and a stationary paper supply holder therefor, of a vertically extending guide frame carried by the reciprocating platen carriage of the writing machine, said guide frame including upwardly extending arms, mounting members 20 detachably engageable with the platen carriage of the conventional writing machine to which the arms are connected, and a cross rod adjustably mounted in said arms over which a paper supply is drawn from the holder to the platen.

25

10. The combination with a writing machine and a stationary paper supply holder therefor, of a vertically extending guide frame carried by the reciprocating platen carriage of the writing machine, said frame including upwardly extending 30 side arms attached to mounting members detachably engaging a platen carriage of a conventional writing machine, and a cross rod carried by the side arms over which the paper supply is freely drawn from the holder to the platen, said cross 35 rod being elevated sufficient distance above the platen to insure an ample length of paper supply between the holder and platen to prevent uneven tension of the portion engaging the platen.

40
